TIRE RACK

Ben W. Harley, Robert C. Shape, and Norris H. Mealy,
Warren, Ohio, assignors to The Warren Steel Special-
ties Corporation, a corporation of Ohio

Application June 30, 1958, Serial No. 51,586

Term of patent 14 years

(Cl. D80—10)

Figure 1 is a side elevational view of a tire rack showing our new design;

Figure 2 is an end elevational view thereof; and

Figure 3 is a perspective view of the tire rack, a portion being broken away for convenience of illustration.

The dotted line showing of tires in Figure 1 is for purposes of illustration only.

The dominant features of our design reside in the portions shown in full lines in the drawing.

We claim:

The ornamental design for a tire rack, substantially as shown and described.
